EXPANDED STRUCTURAL MEMBER

Albert T. Keller, Bethlehem, Charles Schenck, Coopersburg, and Lewis Fine, Bethlehem, Pa., assignors to Bethlehem Steel Company, a corporation of Pennsylvania

Application July 9, 1930, Serial No. 466,614

14 Claims. (Cl. 164—6.6)

Our invention relates to the manufacture of expanded metal bars, beams, columns, girders and the like for use in structural operations.

One of the objects of our invention relates to the manner of forming and mounting the delivery pinch rolls which are adapted to receive and pull the expanded section through the expanding guide, one of the delivery pinch rolls being yieldingly mounted and adapted to exert a constant pressure on the web of the section as it passes between the rolls.

Another object of our invention relates to the angle of forming the sides of the slitting knife edges in such a manner as to relieve the pressure or load in the central slitters.

Another object of our invention relates to the manner of forming the slitting knives of greater height than the thickness of the web of the article being slitted in order to give a clearance between the face of the slitting rolls and the sides of the web, so that the strands will not become elongated during the slitting operation.

In the drawings we have illustrated our invention as used in forming an expanded metal I-beam but we wish it understood that our invention could be used equally well in expanding other shapes as channels, Z-bars and the like if desired.

In the forming of expanded sections such as that illustrated, the beam is first fed between feed rolls to the slitting rolls which advances the beam and pushes it through an expanding guide adapted to expand the web of the bar and finally advances it between the finishing pass of a set of delivery pinch rolls which flattens the web strands and at the same time pulls the expanded metal shape through the expanding guide.

It was found however that after the metal shape left the finishing roll pass of ordinary construction where the rolls had fixed centers or draft that the shape of the bar would be distorted when it issued from the pass.

It has been found by actual practice that rolls with fixed draft having a roll pass similar to that shown in Fig. 5 of the drawings in which the sizes of the roll pass are in contact with the web of the section, but not touching any part of the flanges, with sufficient clearance to allow an increase in the draft without touching the flanges, that the section when it issued from the pass was wider than the width of the pass cut in the rolls, and that the web strands will be buckled or laterally waved, and arch shaped in top plan.

The cause of this action can be easily explained, by referring to Fig. 1 of the drawings it will be noted that while the section in passing in the

direction of the arrow from left to right through the delivery pinch rolls any draft on the web will elongate the strands and due to their angularity, they will move outward from the central bonds in a curved path. This outward motion will increase the width of the section and when the web becomes too thick, the increase in the length of the strand due to the fixed draft will cause the strands to buckle. To overcome this buckling, it was decided to relieve the pass in the delivery rolls so that it made contact on the web portion adjacent to the flanges only with the central portion of the pass out of engagement with the web. It was found however that the section after passing a roll pass having a relieved central portion that the section was somewhat less in width than the pass and in some of the sections the flanges were buckled outwardly between the side bonds and in many cases the strands were torn off where they joined the bonds near the flanges, the reason for this being that any draft placed on the web close to the flanges as described above will elongate the flanges and cause the strands to hinge at the center of the web where the two strands meet.

This hinging action moves the flanges inward and reduces the width of the section and if the flanges are elongated very much, will cause a pull on the strand and will tear them at the bonds where they join the flanges or at the center of the expanded section.

From the foregoing, it is evident that the amount of draft put on the delivery roll and shape of roll is important. To overcome the difficulty experienced, we have found that a strand having means adapted to give a yielding constant pressure on the web of the section can be applied on the delivery pinch rolls which have a pass cut in them as shown in Figs. 1, 3, 5 and 7. This pressure can be applied by means of applying weights as shown in Figs. 7 and 8 or if desired by means of fluid pressure cylinders mounted on the roll housing. With this arrangement the strands are elongated just enough to keep them straight without regard to the thickness of the web of the expanded section.

Having now given a general description of our invention, we will now in order to make the matter more clear, refer to the accompanying four sheets of drawings which form part of this specification and in which like characters of reference refer to like parts:

Fig. 1 is a top plan view of one form of our improved apparatus illustrating the blank in the course of slitting and expansion of the sec-

tion in which one set of slitting rolls are used;

Fig. 2 is a side elevation of the device shown in Fig. 1 with parts in section;

Fig. 3 is a top plan of a modified form of apparatus which is similar to Fig. 1 but showing two sets of slitting rolls;

Fig. 4 is a side elevation of the modification illustrated in Fig. 3 with the ends of the shafts in section;

10 Fig. 5 is an enlarged detail section of the meeting edges of the delivery pinch rolls illustrating the manner of the grooved pass engaging the web of the section;

15 Fig. 6 is an enlarged detail section view illustrating the manner of slitting the bar;

Fig. 7 is a front elevation of the delivery pinch roll stand;

Fig. 8 is a side elevation of the roll stand shown in Fig. 7;

20 Fig. 9 is a detail section view at the top of one of the sides of the delivery pinch roll housing taken on the line 9—9 of Fig. 7; and

Fig. 10 is a top plan view of one of the cap plates for the delivery pinch roll housing.

25 Referring now to the various characters of reference on the drawings and first to Figs. 1, 2 and 5 to 10, the numeral 1 indicates the blank or shape to be expanded, 2 and 3, the feed rolls mounted on shafts 4 and 5 having knurled tractive peripheries 6 adapted to engage the blank and feed it forward to a set of slitting rolls 7 and 8 mounted on shafts 9 and 10. The slitting rolls each have three sets of spaced slitting knife edges 11, 12 and 13 extending from their periphery the set of knife edges on one roll coacting with the cutting knife edge on the opposite roll. The central knife edges 12 are spaced in staggered relation to the two outer sets.

40 By referring to Fig. 6 it will be seen that the shape of the cutting knife edges 12 are such as to make a plurality of central cuts in the blank, the edges 13 of which will be 30° on each side of a vertical line at right angles to the web, or 60° in the included angle, while the two rows of side slits made by the slitting knife edges 11 and 13 are formed to cut the web of the blank at an angle of 15° on the inner side 15 of the vertical center at right angles to the web and 45° on the outer face as at 16. The object of the change in the angularity of the outer slitting knife edges is to throw the metal which is extruded by the knife edges outwardly during the slitting process thereby relieving the load on the center slitting knife edges 12 and more evenly distribute the metal and prevent stretching in the web strands. The slitting knife edges on each roll are adapted to cut half way through the web of the blank and are of greater height than half the thickness of the web in order to give a clearance 17 between the sides of the slitting rolls and the web of the blank. After the blank has passed between the slitting rolls 7 and 8 it is fed between expanding guide 18 of well known construction having grooves on each side to receive the flanges of the blank passing through them in the direction of the arrow and gradually expanding the web of the blank by forcing the strand 19 apart. These strands are connected together centrally at one end by means of bonds 20 and at the other ends opposite the flanges by means of bonds 21.

60 The feed rolls 2 and 3 and slitting rolls 7 and 8 advance the blank between the expanding guide 18. After passing through the guide, the expanded section is received in the pass 22 between a set of delivery pinch rolls 23 and 24

adapted to pull the expanded section through the expanding guide and to straighten the expanded web. These delivery pinch rolls 23 and 24 have their shafts 25 and 26 journaled in bearing blocks 27 and 28 which are mounted in guide-ways 29 and 30 of the frame of a roll stand 31. The side frames of the roll stand 31 are each connected together at the tops by means of a cap plate 32 the ends of which are bifurcated as at 33 to receive the upwardly extending posts 34 of the side frame. These posts are each slotted as at 35 to receive a tapered key 36 for clamping the ends of the cap plates 32 in position. Formed centrally on top of each cap plate and integral therewith near the inner edges is a standard 37 to the upper end of which is pivoted a lever 38 having a bearing surface 39 adapted to engage the top end of a pin 40. This pin 40 extends downwardly through an opening 41 formed in the center of each cap plate 32, the opposite end of each pin engaging the top of the journal boxes 27. Each lever 38 extends horizontally outward and has a weight 42 adjustably mounted thereon by means of which the pressure on the expanded section passing between the delivery pinch rolls may be varied.

45 The shaft 16 of the lower slitting roll 8 is preferably the main drive shaft and has a gear 43 mounted thereon which meshes with idler gears 44 and 45 on either side thereof which are adapted to mesh with a gear 46 on the lower feed roll shaft 5 and gear 47 on the shaft 26 for the lower delivery pinch roll 24. In this manner the feed rolls 2 and 3, slitting rolls 7 and 8 and delivery pinch rolls 23 and 24 are all rotated at the same surface speed. Each pair of feed rolls, slitting rolls and delivery pinch rolls is geared together by means of gears 46, 43 and 47 which are mounted on shafts 4, 9 and 25 respectively and are all adapted to rotate at the same surface rate of speed.

50 The operation of our device is as follows: Assuming that the feed rolls 2 and 3, slitting rolls 7 and 8, and the delivery pinch rolls 23 and 24 are all being driven at the same surface speed, the blank 1 is fed between the knurled feed rolls 2 and 3 which advances it to the slitting rolls the outer slitting knife edges of which are so shaped that they throw the flanges outwardly during the slitting process and thereby relieve the load on the center slitting knife edges and all of the slitting knife edges are of sufficient length to allow for a clearance between the side face of the slitting rolls and the sides of the web strands so that when they cut into the web of the blank it will not elongate the strands. After the blank 1 has passed between the slitting rolls it is advanced into the guide 18 which gradually expands the web of the blank by forcing the strands 19 apart between the bonds 20 and 21. The expanded section is then advanced into the pass 22 of a set of delivery pinch rolls 23 and 24 one of which is yieldingly mounted and adapted to apply a constant pressure on the expanded web of the section sufficient to pull the section through the guide, and thereby elongating the strands just enough to keep them straight as will be more clearly understood by referring to Figs. 1, 5 and 7.

55 In Figs. 3 and 4 we have shown a modification in which two pairs of slitting rolls 48, 49, 50 and 51 mounted on shaft 52, 53, 54 and 55 are used. The first set of slitting rolls 48 and 49 have outer slitting knife edges 56 thereon, while the second set of slitting rolls have the central 60

slitting knife edges 51 formed thereon, otherwise the construction is similar to that described for Figs. 1, 2, 5 to 9 and the same reference numeral will apply thereto.

5 Although we have described and illustrated our invention in considerable detail, we do not wish to be limited to the exact and specific details thereof, as shown and described, but may use such modifications in, substitutions for, or equivalents thereof, as are embraced within the scope of our invention, or as pointed out in the claims.

Having thus described our invention what we claim and desire to secure by Letters Patent is:

15 1. In a machine for expanding metal shapes, means for slitting the metal shape longitudinally of its length, a guide for expanding the metal shape, a pair of delivery pinch rolls mounted in a housing provided with a pass adapted to receive 20 the metal shape after it has emerged from the expanding guide for feeding the expanded shape forward from the expanding guide, slide-ways formed in each side of the housing, journal bearings mounted in the slide-ways for supporting the 25 delivery pinch rolls, a slotted post extending upwardly from the housing on each side of the slide-ways, a cap-plate having bifurcated ends for receiving the slotted posts, a tapered key in each slot for clamping the bifurcated ends of the cap- 30 plates to the top of the housing, a central perforation provided in each of said cap-plates, a pin mounted in each perforation having its lower end engaging the top journal bearing of the top delivery pinch roll, a standard opposite each perforation formed integral with each cap-plate, a 35 weighted lever pivoted to each standard and engaging the top of the pin adapted to exert a constant pressure on the expanded shape as it passes between the delivery pinch rolls, and means for 40 adjusting the weight on the lever.

2. In a machine for making open work metal shapes, a pair of slitting rolls for slitting the web of the shape longitudinally of its length, a pair of feed rolls for advancing the shape between the slitting rolls, a plurality of cutting knife edges extending outwardly from the periphery of the slitting rolls, the cutting knife edges on one slitting roll coacting with the cutting knife edges on the other slitting roll, the combined height 50 of the two cutting knife edges being of greater height than the thickness of the web of the shape, means for expanding the blank after slitting, and delivery pinch rolls tractively engaging the expanded metal shape emerging from the expanding means, and weighted lever means connected to one of the pinch rolls adapted to project one of the delivery pinch rolls towards the other to exert a yielding constant pressure on the expanded web of the metal shape as it passes between the rolls.

3. In a machine for making open work metal shapes provided with a thickened central portion, a pair of slitting rolls for slitting the thickened web of the shape longitudinally of its length to form strands, a pair of feed rolls for advancing the shape between the slitting rolls, a plurality of cutting knife edges extending outwardly from the periphery of the slitting rolls the outer side faces of the cutting knife edges having a greater angularity from a plane at the center of the cutting knife edges than the inner side faces adapted to throw the flanges outwardly during the slitting operation, the cutting knife edges on one slitting roll coacting with the cutting knife edges on the other slitting roll, the combined height of the two

cutting knife edges being greater than the thickness of the web of the shape, means for expanding the shape after slitting, delivery pinch rolls provided with a pass adapted to tractively engage the expanded metal shape emerging from the expanding means and adapted to exert a yielding constant pressure on the expanded web of the metal shape to straighten the strands as the expanded shape passes between the pinch rolls, and means for driving the feed rolls, slitting rolls 10 and pinch rolls in synchronism.

4. In a machine for making an open work metal shape from a blank provided with a thickened central web portion, feed rolls for moving the shape forward, slitting rolls for engaging the shape during the movement thereof to slit the thickened metal web portion at spaced intervals longitudinally of its direction of movement to form strands, means for expanding the shape laterally after the slitting operation, a set of 20 continuously driven delivery pinch rolls for tractively engaging and rolling the thickened strand portion of the shape after emerging from the expanding means, and weighted lever means for moving one of the pinch rolls towards the other 25 pinch roll to exert a constant yielding pressure on the strands of the shape as it passes between the pinch rolls.

5. In a machine for making an open work flanged metal shape from a blank having a thickened central web portion, feed rolls geared together for moving the shape forward, slitting rolls geared together for engaging the shape during the movement thereof to slit the thickened metal web portion longitudinally of its direction of movement to form strands, an idler gear directly connecting the gearing of the feed rolls with the gearing of the slitting rolls, means for expanding the shape laterally at right angles to the flanges after the slitting operation, a set of delivery 30 pinch rolls geared together for tractively engaging and rolling the thickened strand portions of the shape after emerging from the expanding means, an idler gear for directly connecting the gearing of the slitting rolls with the gearing for 35 the delivery pinch rolls, a roll stand for the pinch rolls having slide-ways formed therein at each side thereof movable and stationary journal bearing blocks mounted in the slideways, shafts for the pinch rolls journaled in the bearing 40 blocks, and weighted lever means connected to each of the movable bearing blocks for moving one of the pinch rolls towards the other pinch 45 roll and adapted to exert a constant yielding pressure on the thickened web portion of the 50 shape as it passes between the pinch rolls.

6. In a machine for making an open work flanged metal shape from a blank provided with a thickened central web portion, feed rolls for advancing the shape, slitting rolls engaging the shape during the movement thereof to slit the thickened metal web portion longitudinally of its direction of movement to form strands, means for expanding the shape laterally at right angles to the flanges after slitting, a set of delivery pinch 60 rolls for tractively engaging and rolling the thickened strand portion of the shape after emerging from the expanding means, a roll stand for the pinch rolls having slide-ways formed therein at each side of the stand, a stationary 65 and movable bearing block mounted in each slide-way, shafts for the pinch rolls journaled in the bearing blocks, a cap-plate secured to each side of the roll stand provided with a central opening, a pin extending through each opening 70

75

with its lower end engaging the movable bearing block, a post formed integral with each cap-plate, a lever having its inner end pivotally connected to each of the top ends of each post and engaging the top end of the pins at an intermediate point, and an adjustable weight mounted on the outer ends of each lever adapted to move one of the pinch rolls towards the other pinch roll to exert a constant yielding pressure on the web of the shape as it passes between the said pinch rolls.

7. In a machine for making an open work flanged metal shape from a blank having a thickened central web with reduced portions connecting the flanges, feed rolls for moving the shape forward, means for slitting the thickened portion of the shape longitudinally of its length to form strands, a guide for expanding the shape, a pair of delivery pinch rolls mounted in a housing provided with a pass adapted to receive the metal shape after it has emerged from the expanding guide for advancing and rolling the strands of the expanded shape after leaving the expanding guide, slide-ways formed in each side of the housing, journal bearings mounted in each of the slide-ways, a weighted lever for independently applying pressure to each of the top journal bearings for the top pinch roll for projecting one of the pinch rolls towards the other adapted to exert a yielding constant pressure on the strands of the expanded shape as it passes between the delivery pinch rolls.

8. In a machine for making open work metal shapes from a blank having a central web portion and flanged edges, feed rolls for advancing the blank, slitting rolls having coacting knives having side edges of one angularity for forming longitudinally extending spaced slits in the central portion of the web, coacting knives having side edges of a different angularity than those forming the central slits for forming longitudinally extending slits in the web of the blank at an intermediate point in staggered relation between the central slits and the flanges adapted to form strands, said side edges of the knives being adapted to extrude and throw a major portion of the metal displaced outwardly in forming the slits in the intermediate portion of the web of the shape, means for laterally expanding the shape, and a set of delivery pinch rolls in spaced relation with the inside of the flanges of the shape adapted to exert a yielding constant pressure on the central portion of the web to slightly elongate and straighten the strands.

55 9. In a machine for making open work metal shapes from a blank provided with a central web portion and flanged edges, feed rolls for advancing the blank, slitting rolls having coacting knife edges for forming spaced slits in the central longitudinal portion of the web, a pair of slitting rolls having coacting knives with side edges of a different angularity than those forming the central slits for forming longitudinally extending spaced slits in the web of the blank at an intermediate point between the central slits and the flanges in staggered relation with said central slits to form strands, means for laterally expanding the shape, and a set of delivery pinch rolls provided with a pass in spaced relation with the inside of the flanges of the shape adapted to exert a yielding constant pressure on the central portion of the web to slightly elongate and straighten the strands of the shape as it passes between the said pinch rolls.

75 10. In a machine for making open work metal

shapes from a blank provided with a thickened central web portion and flanged edges, said web being provided with reduced regions between the thickened central portion and the flanges, feed rolls for advancing the blank, slitting rolls having coacting knife edges with sides of different angularity for forming longitudinally extending spaced slots in the central and intermediate portion of the thickened web portion to form strands without elongating the metal therein, means for expanding the shape, and a set of delivery pinch rolls provided with a pass adapted to engage the outside of the flanges and in spaced relation with the inside of the flanges of the shape adapted to exert a yielding constant pressure on the web to slightly elongate and flatten the strands of the shape as it passes between the pinch rolls.

11. In a machine for making open work metal shapes with a central web portion and flanged edges, feed rolls for advancing the blank, slitting rolls having coacting knives for slitting the central portion of the web and coacting knives having side edges of a different angularity adapted to displace a major portion of the metal outwardly to relieve the pressure on the central slitting knives for slitting the web at intermediate points and in staggered relation between the central slits and the flanges of the blank to form strands, means for laterally expanding the shape, and a set of delivery pinch rolls provided with a pass in spaced relation with the inside of the flanges of the shape adapted to engage the central portion of the web to slightly elongate and straighten the strands by exerting a yielding constant pressure on the strands of the shape as it passes between the pinch rolls.

12. In a machine for making open work metal shapes from a blank provided with a thickened central web portion and flanged edges, said web being provided with reduced regions between the thickened central portion and the flanges, feed rolls for advancing the blank, slitting rolls provided with coacting knives adapted to form longitudinally extending slits in the central portion of the web, slitting rolls provided with coacting knives having cutting edges of a different angularity than the central coacting slitting knives adapted to throw the metal which is extruded by the knife edges outwardly during the slitting operation thereby relieving the pressure on the central slitting knife edges to more evenly distribute the metal and prevent stretching of the strands, means for laterally expanding the shape, and a set of delivery pinch rolls provided with a pass adapted to engage the central thickened portion of the web to slightly elongate and straighten the strands by exerting a yielding constant pressure on the strands of the shape as it passes between the pinch rolls.

13. In a machine for making an open work metal shape from a blank provided with a thickened central web portion and flanged edges, said web being provided with reduced regions between the thickened central portion and the flanges, slitting rolls adapted to form longitudinal slits in the central portion of the thickened web portion, slitting rolls for forming spaced longitudinal slits in the thickened web portion at an intermediate point between the flanges and the central slits to form strands, means for expanding the shape laterally after the slitting operation, a set of continuously driven delivery pinch rolls for tractively engaging and rolling the

strands of the shape after emerging from the expanding means thereby slightly elongating and straightening the strands, and means for exerting a yielding constant pressure on the strands of the shape as it passes between the pinch rolls.

14. In a machine for making an open work metal shape from a blank provided with a thickened central web portion and flanged edges, said web being provided with reduced regions between the thickened central portion and the flanges, feed rolls for advancing the blank, slitting rolls adapted to slit the central portion of the thickened web portion, slitting rolls mounted adjacent to the rolls for forming the central slits adapted to form slits in the thickened web

portion at an intermediate point between the flanges and the central slits and in staggered relation with said central slits to form strands, means for laterally expanding the shape after the slitting operation, a set of continuously driven delivery pinch rolls for tractively engaging and rolling the strand portions of the shape after emerging from the expanding means thereby slightly elongating and straightening the strands, and means for exerting a yielding constant pressure on the strands of the shape as it passes between the pinch rolls.
